[57] CLAIM

The ornamental design for a cup with spoon holder, as shown and described.

DESCRIPTION

FIG. 1 is a front-elevational view of a first embodiment of a cup with a spoon holder having rungs showing my new design, the rear being a mirror image thereof; FIG. 2 is a right-side elevational view thereof; FIG. 3 is a left-side elevational view of both embodiments;

FIG. 4 is a top-plan view of both embodiments; FIG. 5 is a bottom-plan view of both embodiments; FIG. 6 is a front-elevational view of a second embodiment of a cup with a spoon holder having a channel showing my new design, the rear being a mirror image thereof;

FIG. 7 is a right-side elevational view thereof; FIG. 8 is a right-side elevational view of the first embodiment with a spoon being shown in broken lines for environmental purposes only and forms no part of the claimed design; and

FIG. 9 is a right-side elevational view of the second embodiment with a spoon being shown in broken lines for environmental purposes only and forms no part of the claimed design.

FIG. 1FIG. 2FIG. 3FIG. 4FIG. 5FIG. 6FIG. 7FIG. 8FIG. 9
